UNITED STATES PATENT OFFICE.

J. EDWIN GILES, OF HAZLETON, PENNSYLVANIA.

REGULATOR FOR DYNAMO-ELECTRIC MACHINES.

SPECIFICATION forming part of Letters Patent No. 290,412, dated December 18, 1882.

Application filed September 1, 1883. (No model.)

To all whom it may concern:

Be it known that I, J. EDWIN GILES, of Hazleton, in the county of Luzerne and State of Pennsylvania, have invented a new and Improved 5 Current-Regulator for Dynamo-Electric Machines, of which the following is a full, clear, and exact description.

My invention relates to the class of current-regulators in which the commutator-brush is 10 moved toward or from the neutral point. Regulators of this class, as heretofore constructed, move the brushes with a uniform speed, and are in no way influenced in the speed of their movement by variations in the strength of the current. Consequently a sudden and great 15 augmentation of the current endangers the armature, destroys the carbon filaments of incandescent lamps, and renders the light of arc lamps unsteady. My improvement is designed 20 to obviate all these difficulties by insuring a gradual movement of one or both of the commutator-brushes under all ordinary variations in the strength of the current, and a very rapid movement of one or both brushes with 25 a sudden and considerable increase in the strength of the current.

My invention consists in the combination, with the swiveled brush-holder of a dynamo-electric machine, of a regulating-screw capable of being revolved slowly in either direction by pawl-and-ratchet mechanism operated by the power driving the dynamo, and controlled by electro-magnets receiving a current from the dynamo.

It further consists in apparatus for imparting to the regulating-screw a more rapid movement, the said apparatus being controlled by another set of magnets affected only by a strong current.

Reference is to be had to the accompanying drawings, forming part of this specification, in which similar letters of reference indicate corresponding parts in both the figures.

Figure 1 is a side elevation of my improved 45 current-regulator. Fig. 2 is a front view, and Fig. 3 is a detail view of the mechanism for throwing the friction-wheels into gear.

Upon the shaft of a dynamo-electric machine, or upon a bearing concentric therewith, 50 is placed the brush-holder A, which is capable of turning on its bearing in either direction. The brush-holder A has an arm, B, sup-

porting the ordinary commutator-brush, C, in contact with the commutator-cylinder D. A slotted arm, E, projects from the brush-holder and receives into its slot a pin projecting from the nut a on the screw a', formed on the shaft F. The screw-shaft F is journaled in a box, b, on the dynamo, and in a frame, G, secured to the dynamo-base. A friction-wheel, H, 55 ratchet-wheel I, and oscillating plate J are placed on the screw-shaft F, near the frame G, in the order named, the friction-wheel H being nearest the frame. The oscillating plate J moves upon the screw-shaft F, while the friction-wheel H and ratchet-wheel I are fixed to the shaft.

A shaft, K, having upon one end a pulley, c, and upon the other end a friction-wheel, d, is journaled in a frame, L, pivoted to the frame G, and capable of being moved laterally. The friction-wheel d carries a crank-pin, e, which connects with the stud f on the oscillating plate J by means of the connecting-rod g. The pulley c takes power through a belt from 75 some part of the dynamo, or from other suitable source, and as the shaft K revolves the plate J is oscillated. The upper corners of the plate J project above the ratchet-wheel, and carry two oppositely-arranged pawls, h h'. 80 A pin, i, projects from the side of each pawl, and is pressed by a spring, j. Below the spring j a three-arm lever, l, is pivoted to the plate J. The arms l l' of the lever l are pressed by the pins i of the pawls h h', and the arm m 85 of the said lever extends downward between two electro-magnets, n n', secured to the oscillating plate J, and the said arm m carries an armature, m', common to both magnets. The lower end of the arm m is connected with two 90 spiral springs, o o', extending in opposite directions and secured to the plate J. When a current is sent through one or the other of these magnets, one or the other of the pawls h h' is allowed to drop sufficiently to engage the 95 ratchet-wheel I.

To the frame G is secured an electro-magnet, M, with its poles facing the frame L. The frame L, being made of iron, forms the armature of the magnet M.

To an arm, p, projecting from the frame L is pivoted a right-angled lever, q, whose vertical arm r rests against a contact-screw, s, and carries a contact-screw, t. The horizontal arm

of the lever q has at its free end an armature, u , from which a wedge, v , projects downward between one pole of the magnet M and the frame L . Above the armature u is supported 5 an electro-magnet, N , capable of being operated by a strong current only.

An axial magnet, O , is connected in the main circuit of the dynamo or in a shunt by its terminals w , and two wires, $x x'$, convey a 10 portion of the current to the switch P , which sends a current through one or the other of the magnets $n n'$ and through the auxiliary magnets $M N$ whenever abnormal variations in the strength of the current occur. The 15 movable core A' of the axial magnet O carries two contact-pieces, $B' B''$, which are insulated from each other and from the core. These contact-pieces are in electrical communication with the wires $x x'$ through the springs 20 $C' C''$, these springs serving the double purpose of conveying the current and of lifting the core A' and the contact-pieces $B' B''$. Below the contact-pieces $B' B''$ there are two contact-pieces, $D' D''$, secured to the top of the 25 axial magnet and insulated from each other. The contact-piece D' is connected by a wire, a'' , with one terminal of the magnet n' , and the contact piece D'' is connected by a wire, a''' , with one terminal of the magnet N . 30 Above the contact-pieces $B' B''$ are two contact-screws, $b' b''$, insulated from each other, and connected with the terminals of the magnet n by the wires $c' c''$. A wire, d' , connects the magnet n' with the insulated bracket e' , 35 which supports the contact-screw s . A wire, f' , connects one terminal of the magnet M with a contact-point, g' , opposite the screw t , the other terminal of the said magnet M being connected with the wire a'' by the wire h'' . 40 A commutator-brush, E' , is supported by the pillar F' below the commutator-cylinder, in position to oppose the movable brush C . When it is desirable or necessary to have a 45 third brush for the purpose of regulation, a stationary brush, G' , is supported in contact with the top of the commutator-cylinder by a pillar, as shown in dotted lines in Fig. 2.

When the current is normal, the contact-points $B' B''$ occupy a middle position between 50 the contact-screws $b' b''$ and the contact-pieces $D' D''$; but should the current fall below the normal the core A' of the axial magnet O is relieved, allowing the springs $C' C''$ to raise it, together with the contact-pieces $B' B''$, bringing 55 the said contact-pieces into contact with the screws $b' b''$. The current then flows through the magnet n , drawing armature m' toward it, releasing the pawl h' , which, being kept in constant oscillation, acts on the ratchet-wheel 60 I , slowly turning the screw-shaft F , thereby turning the brush-holder A , advancing the brush C toward the position of maximum current. When the current arrives at its normal strength, the axial magnet O draws down the 65 core A' , breaking contact between $b' b''$ and $B' B''$, when the armature m' will be released, and the springs $j o o'$ will return it to its mid-

dle position between the magnets $n n'$, and in so doing will disengage the pawl h' from the ratchet-wheel I . Should the current increase 70 in strength, the core A' will be drawn downward until the contact-pieces $B' B''$ touch the contact-pieces $D' D''$, when the current will flow through the wire a'' , magnet n' , wire d' , bracket e' , screw s , lever q , wire f'' , magnet N , 75 wire a''' , to the contact-pieces $D'' B''$, through the rest of the circuit to the machine. The armature m' is then drawn toward the magnet n' , the pawl h is released, when it acts upon the ratchet-wheel I , causing the screw-shaft to 80 revolve slowly and move the brush C toward the point of minimum current, and when the current is reduced to its normal condition, contact between $B' D'$ and $B'' D''$ is broken and the pawl h is disengaged from the ratchet-wheel; but should the current increase to an 85 extraordinary extent the magnet N becomes active, drawing up the armature u , thus removing the wedge v from between the magnet M and the frame L , at the same time breaking 90 contact between the lever q and screw s and making contact between the screw t and contact-point g' . The magnet n' is by this means rendered inactive, allowing the pawl h to be withdrawn from the ratchet-wheel, and at the 95 same time the current is made to pass from wire a'' through the wire h'' , magnet M , wire f' , contact g' , screw t , lever q , wire f'' , magnet N , wire a''' , and through the rest of the circuit to the dynamo. The magnet M draws the 100 pivoted frame L forward, bringing the friction-wheel d into contact with the friction-wheel H , when the screw-shaft F is rapidly revolved, bringing the brush C quickly toward the point of minimum current. When the current attains its normal strength, contact between the pieces $B' D'$ and $B'' D''$ is broken, 105 and all of the parts regain their normal position.

Having thus fully described my invention, I 110 claim as new and desire to secure by Letters Patent—

1. In a current-regulator for dynamo-electric machines, the combination, with a regulating-screw, a ratchet-wheel, an oscillating plate, 115 and means, substantially as described, for oscillating the same, of two electro-magnets, an armature common to both magnets, and springs for returning the armature to its normal position when released by either of the magnets, 120 the pawls, magnets, armatures, and springs being carried by the oscillating plate, as set forth.

2. In a current-regulator for dynamo-electric machines, the combination, with the movable commutator-brush, of two electrically-controlled trains of regulating mechanism, one for imparting a slow movement to the brush under ordinary changes of the current, and the other for imparting a rapid movement to the brush under extraordinary changes in the current. 125

3. In a current-regulator for dynamo-electric machines, the combination, with the mag-

nets $n n'$ and auxiliary magnets M N, of the axial magnet O, provided with contact-pieces D' D'' and the contact-screws b' b'', and its core provided with the contact-pieces B' B'', substantially as herein shown and described.

4. In a current-regulator for dynamo-electric machines, two oppositely-arranged pawls, h h', the three-arm lever m, magnets $n n'$, oscillating plate J, and ratchet-wheel I, in combination with the brush-regulating screw.

5. The combination, in a current-regulator for dynamo-electric machines, of the friction-wheel d, swinging frame L, and magnet M, with the friction-wheel H and brush-regulating screw.

6. In a current-regulator for dynamo-electric machines, the magnet N and lever q, provided with the wedge v and armature u, in combination with the pivoted frame L.

7. In a current-regulator for dynamo-electric machines, the magnets M N, lever q, pivoted frame L, and friction-wheels d H, in combination.

8. In a current-regulator for dynamo-electric machines, the magnet N, adapted to be affected by strong currents, the armature-lever q, carrying the contact-screw t, the contact-point g', insulated screw s, magnet M, and the circuit-wires, in combination, whereby a strong current traversing the magnet N will cut out the magnet of the slow regulating mechanism and put in circuit the magnet M of the quick regulating mechanism, as specified.
